United States Patent Office

Des. 227,850
Patented July 24, 1973

227,850

CAMP STOVE

Raymond E. Benson, 535 S. East Ave.,
Oak Park, Ill. 60304

Filed May 21, 1971, Ser. No. 145,993

Term of patent 14 years

Int. Cl. D7—02

U.S. Cl. D7—110

FIG-2

FIG-3

FIG-1

FIG-4

FIG. 1 is a perspective view of the camp stove of this invention shown closed for carrying or storage;

FIG. 2 is a front view of the stove of this invention;

FIG. 3 is an end view of the stove of this invention; and

FIG. 4 is a perspective view of the stove of this invention shown open and erected for use.

The undisclosed end is substantially the same in appearance as the end shown except for the omission of the carrying handle and fuel fitting, and the undisclosed rear is substantially the same in appearance as the front except for the omission of the knobs and the latching elements.

I claim:

The ornamental design for a camp stove, as shown and described.
